F. E. DIXON,
Sash-Fasteners.

No. 7,752.

Patented Sept, 8, 1874.

UNITED STATES PATENT OFFICE.

FREDERICK E. DIXON, OF TORONTO, CANADA.

DESIGN FOR SASH-FASTENERS.

Specification forming part of Design No. 7,752, dated September 8, 1874; application filed September 3, 1874.
[Term of Patent 7 years.]

To all whom it may concern:

Be it known that I, FREDERICK E. DIXON, of the city of Toronto, in the county of York and Province of Ontario, Dominion of Canada, have invented a Sash or Window-Frame Holder and Fastener, of which the following is a specification:

The nature of my design is fully represented in the accompanying drawing, to which reference is made, it being a front view thereof.

The central or horizontal portion of the design follows in its outline the shape of the corresponding part of a Maltese cross, while the upper and lower members of the design are varied, as shown, the upper one rising inward and being surmounted by a discal ornament, *a*, centrally perforated, the lower one falling inward from parallel lines extending downward from the inner terminals of the horizon-

tal part of the design, and ending in a heart-shaped figure. The inner portion of the design is depressed or sunken, leaving a raised border, *c*, surrounding it, the upper discal and lower heart-shaped figures being upon the same plane with the border. Both sides of the design, which are parallel, present the same appearance, and the entire edge or outline is at a right angle with the faces.

What I claim as my invention is—

The design for a sash or window-frame holder and fastener, as shown in the accompanying drawing, and herein described.

In witness whereof I have subscribed my name hereto in the presence of two witnesses.

F. E. DIXON.
